CLAIM

The ornamental design for a tool accessory hub, as shown and described.

DESCRIPTION

FIG. 1 is a perspective view of the tool accessory hub; FIG. 2 is a top plan view of the tool accessory hub of FIG. 1, the bottom plan view being identical thereto; FIG. 3 is an end view of the tool accessory hub of FIG. 1; and, FIG. 4 is a side elevational view of the tool accessory hub of FIG. 1, the opposite side elevational view being identical thereto.

The broken-line disclosure of elements is understood to represent portions of the article in which the design is embodied, but which form no part of the claimed design.

1 Claim, 1 Drawing Sheet
